UNITED STATES PATENT OFFICE

EDWARD BOSWORTH GRIER, OF WEST HARTFORD, CONNECTICUT, ASSIGNOR TO THE ARROW-HART AND HEGEMAN ELECTRIC COMPANY, OF HARTFORD, CONNECTICUT, A CORPORATION OF CONNECTICUT

DESIGN FOR A FACE PLATE OR SIMILAR ARTICLE

Application filed February 23, 1929. Serial No. 30,184. Term of patent 14 years.

To all whom it may concern:

Be it known that I, EDWARD BOSWORTH GRIER, a citizen of the United States, residing at West Hartford, in the county of Hartford and State of Connecticut, have invented a new, original, and ornamental Design for a Face Plate or Similar Article, of which the following is a specification, reference being had to the accompanying drawing, forming part thereof.

The figure is a plan view of a face plate or similar article, showing my new design.

I claim:

The ornamental design for a face plate or similar article, as shown.

In testimony whereof I have signed my name to this specification.

EDWARD BOSWORTH GRIER.
